OUTSOLE TRIMMING AND CHANNELING MACHINE.

1,118,883.

Specification of Letters Patent.

Patented Nov. 24, 1914.

Application filed August 1, 1913. Serial No. 782,458.

To all whom it may concern:

Be it known that I, FELIX E. VALOIS, a citizen of the United States, residing at Haverhill, county of Essex, State of Massachusetts, have invented a certain new and useful Improvement in Outsole Trimming and Channeling Machines, of which the following is a specification, reference being had therein to the accompanying drawings.

10 My invention relates to that class of machines which are employed in boot and shoe factories to trim off the protruding edge of the outsole of a boot or shoe while on the last, and to cut the groove or channel in 15 which the stitching is laid. The machine is employed in the manufacture of welt shoes and is of the type ordinarily known as a "rough rounder and channeler" but the devices hereinafter described improve 20 the operation of the machine to such an extent that a relatively smooth edge is produced and therefore the machine is not properly termed a rough rounder.

Heretofore, in machines of this class so 25 far as known to me it has been customary to employ an automatic feed mechanism by which the work is advanced at a predetermined rate of speed to the trimming and channeling knives. The speed of the feed 30 depends solely on the speed at which the machine is run and the operator has no control over it, except by changing the speed of rotation of the machine. It results therefore that the machine is speeded to 35 feed the shoe forward at a rate which will enable a poor or slow workman to use it and a rapid and skilled workman can do no more work on it than a slow workman. In the machine embodying my invention no 40 feeding means is employed, and the operator feeds the shoe through the machine by hand, at whatever speed he finds convenient. It therefore results that the machine is adapted for use by both rapid and slow 45 workmen without any change or modification and in practice it is found possible to run the machine at a speed far in excess of that of any other machine of this type, so far as known to me. It is also particularly 50 adapted to difficult work, because the workman may feed the shoe as slowly as is necessary at a difficult place, as for instance around the toe of a pointed shoe. The so-called Baltimore edge may be produced by 55 the machine, and its production is under the

control of the operator, but without requiring special attention or care on his part. No adjustment is required for different sizes of shoes, except that the position of the so-called finger grips on the flexible connection will ordinarily be varied according to the different sizes of shoes.

The machine automatically forms an edge having an amount of Baltimore which is proportioned to the length of the edge to 65 which it is applied.

The mechanism described herein by means of which the production of the Baltimore edge is controlled by the operator is believed to be wholly novel, and to be applicable 70 to various kinds of machines, such for instance as outsole sewing machines for guiding the working instrumentalities thereof. Therefore in the succeeding claims I have claimed it broadly and independently of the 75 working instrumentalities of the outsole trimming machine shown and described herein.

During its passage through the machine the newly trimmed edge of the sole and the 80 inside edge of the trimmings cut off by a trimming knife rest against a member which for convenience I term the "feed stop and guide." This member, together with the crease guide, forms the means which enable the operator to produce the proper edge 85 on the shoe as it is fed by hand through the machine. The feed stop and guide also prevents the shoe being fed forward so fast that the trimming knife will skip, since the 90 feed stop and guide will not permit the shoe to be fed farther than the end of the preceding cut made by the trimming knife, and therefore makes it possible to feed the work by hand instead of by automatic feed- 95 mechanism, as has heretofore ordinarily been done. Since the shoe is guided by the feed stop and guide which engages the edge of the sole as well as by the crease guide which rests on the upper, no bunch or ir- 100 regularity is made in the sole when the operating instrumentalities pass by the seam of the tip. I believe that the feed stop and guide is also capable of useful application to machines having automatic feeds. While 105 I have described the machine embodying my invention as constructed without an automatic feed, I do not limit myself to this construction as an automatic feed may be easily applied to the machine and will in 110

no way interfere with the operation of the other parts of the machine. As automatic feeds are old and well known in the shoe machinery art, it has not been thought necessary to show or describe the same in detail in the present specification.

The trimming knife is given an exceedingly rapid reciprocation and therefore makes a great many more cuts for a given 10 distance than machines of this kind have ordinarily made and by this means the edge of the sole is trimmed perfectly smooth.

In the machine shown in the drawings herein, the channel knife and hammer are 15 withdrawn to enable the operator to insert or remove the work by the action of a pedal and the position of the channel knife relatively to the edge of the outsole as well as the position of the trimming knife during 20 the operation on the shank and the production of a Scotch edge are both controlled by another pedal, but the two pedals are not in use simultaneously, and therefore may both be conveniently operated by the 25 workman's left foot.

In the drawings, Figure 1 is a side elevation of a machine embodying my invention. Fig. 2 is a front elevation of the machine. Fig. 3 is a top plan view. Fig. 4 is a side 30 view of the crease-guide, hammer, channel knife, trimming knife, and feed stop and guide showing the relative position of the various parts during the operation upon a shoe. Fig. 5 is a view of the working instrumentalities of the machine. In this view the machine is about to begin to trim the shank of a right shoe, having just completed the production of the Baltimore edge. Fig. 6 is a detail of the channel knife actuating mechanism. Fig. 7 is a section on line 35 7-7 Fig. 3 looking in the direction of the arrows. Fig. 8 is a detail showing the relations between the trimming knife and hammer. Fig. 9 is a view of a modification 40 showing mechanism for moving the feed stop and guide during the trimming of the sole.

The principal working instrumentalities of the machine consist in the trimming knife 50 11, which trims the edge of the sole, the channel knife 12 which cuts the channel in the bottom of the shoe; the anvil 13 (see Fig. 2) against which the trimming knife operates; the hammer 14 by means of which 55 the stock is held stationary during the cutting movement of the channel knife, and the welt and sole are compressed and flattened; the feed stop and guide 15 (see Fig. 2) the functions of which are hereinafter 60 fully set forth; and the crease guide 16 by the movements of which the width of the edge of the shoe is determined.

To enable the following description to be 65 more readily understood the operation of the working instrumentalities of the ma-

chine will be shortly outlined. The shoe is inserted between the crease guide 16, the anvil 13 and the hammer 14, and then the hammer advances and clamps and compresses or beats the sole and welt against 70 the crease guide. The hammer then remains stationary in this position momentarily. During this time, the channel knife 12 makes its cutting movement by swinging in a horizontal plane. At the same time, the 75 trimming knife 11 makes a cut through the edge of the sole. When the hammer has moved back and released the work the operator moves it forward for a short distance limited by the feed stop and guide 15. The 80 shoe rests against the crease guide 16 at the cutting point and the newly trimmed edge engages the under side of the feed stop and guide 15 while the upper side of said feed stop and guide is engaged by the under edge 85 of the trimmings. The width of the edge is controlled by the crease guide 16 which rests against the upper, therefore as the shoe is filled by the last, the shape of the edge of the shoe is determined by the shape of the 90 last. In the machines shown herein, the formation of the Baltimore edge is also controlled by the position of the crease guide 95 16. As long as the crease guide 16 remains stationary, an edge of even width *i.e.* Scotch edge is formed, but if the crease guide is pushed down gradually a Baltimore edge is produced. The crease guide is moved by a treadle to produce the Scotch edge and to produce the Baltimore edge it is moved by a 100 train of mechanism actuated by a chain to which is attached a finger grip or "medal" which is seized by the hand of the operator and held firmly against the bottom of the shoe so that as the shoe progresses through the machine, the chain or other flexible member is pulled out and the crease guide given a corresponding movement up or down as the case may be, thereby varying 105 the width of edge and forming the Baltimore edge.

The anvil 13 is secured to the frame A of the machine and is stationary and rigid and affords a bearing against which the trimming knife cuts.

At B is shown the driving shaft of the machine. On the shaft B is an eccentric 17 surrounded by an eccentric strap 18. The eccentric strap 18 is forked at its forward end, as is shown in Fig. 3, the two fork members being designated 181 and 182 respectively.

The hammer 14 is pushed forward against the work by the member 182, there being a heavy spring 19 interposed so that when the pressure exerted on the work by the hammer reaches a predetermined amount, the spring will yield and injury will not be done to the work, nor will the machine be strained. The eccentric strap actuates the 125 130

trimming knife 11, being pivotally secured to it by a pin 22 which extends through both members of the work. The trimming knife 11 is secured by the bolt 20 to the forward 5 end of the knife bar 21, being adjustable thereon by means of the said bolt 20.

The knife bar 21 is not notched on the side next the hammer, as shown at *a* and the said notch is engaged by a projection *b* on 10 the adjacent side of the hammer 14. The length of the projection *b* is less than the length of the notch *a*, and the spring 19 which is interposed between the fork member 182 and the hammer 14 holds the hammer 15 in its extreme forward position with the shoulder of the projection *b* against the forward end of the notch *a* except when the nose of the hammer is in contact with the sole of the shoe, at which time the hammer 20 is pushed back for a distance determined by the thickness of the stock. From the foregoing it will be seen that the trimming knife and the hammer reciprocate together, except for the relative motion occurring just as 25 the trimming knife passes through the stock, during which time the hammer is stationary and clamps the stock firmly against the crease guide 16.

The trimming knife bar 21 carries on its underside a stud 23 for a cam roll 24. This cam roll 24 actuates the channel knife bar holder and the channel knife bar in the following manner: The channel knife bar 25, to which the channel knife 12 is adjustably secured by the screw 26, is mounted on a lever 27 which for convenience I call the channel knife bar holder. Said channel knife bar 25 is supported on the holder by means of a horizontal pivot 28 for a purpose to be hereinafter more fully explained. The holder 27 has an arm *c* extending rearwardly, which is pivoted at 29 to the frame of the machine, and on which the holder is 35 swung by the movement of the trimming knife. Secured to the top of the knife bar holder 27 is a plate 30, see also Fig. 7, in which is a cam groove 31. The cam roll 24 secured to the under side of the trimming knife bar moves in the cam groove 31 and 40 as the trimming knife bar 21 moves forward and back the holder 27 and consequently the channel knife bar 25 is swung about the pivot 29 thereby giving to the channel knife the properly timed movement in a 45 horizontal plane to cut the channel. The cutting movement of the channel knife *i. e.* the movement toward the right as seen in Fig. 6, is timed to occur while the trimming knife is making its cut and the stock is held 50 stationary between the nose of the hammer 14 and the crease guide 16.

The channel knife 12 is raised and lowered to vary the position of the channel with regard to the edge of the shoe in the 55 following manner: As previously stated

the channel knife bar 25 is supported in the knife bar holder 27 on the horizontal pivot 28. The groove *d* in the knife bar holder within which the channel knife bar holder is received is deep enough to allow the 70 channel knife bar to swing in a vertical plane the requisite amount. The downward movement of the knife is limited by an adjustable stop which consists of a bolt 301 in a lug 32 on the front end of the 75 channel knife bar holder. The lock nut 33 serves to render permanent the adjustment of the bolt 301. To the rear end of the channel knife bar 25 is secured a link 34 which is itself also secured to the treadle 80 connection 35 operated by a treadle 66 which I call the control treadle. To permit the channel knife bar to swing the requisite amount, the rear edge of the plate 30 is cut away on the under side as shown 85 at 36. The rear end of the channel knife bar 25 is engaged by a spring 37 which tends to hold the knife bar down on the stop bolt 301, so that when the parts are in their normal position *i. e.* at rest, the channel knife is in its lowest position and which is the position which it occupies when operating upon the shank of the shoe where it is desirable to have the channel cut at a 90 distance from the edge of the shoe to enable 95 the outsole sewing machine to operate successfully. As the operator moves the shoe through the machine and reaches the point between the ball and the shank he depresses the treadle and this brings the channel knife 100 bar to the edge of the shoe so that from then on the channel is cut in proper position around the sole of the shoe. When the knife again reaches the point between the ball and the shank the treadle is released so that along the shank the channel is cut at a distance from the edge of the shoe. The spring 37 previously referred to also tends to hold the channel knife bar 105 as far forward as possible so that the knife 110 will cut the channel to the full depth for which the knife is set. The depth of the channel is varied by changing the position of the knife 12 on the knife bar 25 by means of the screw 26. The tension on the spring 115 37 is adjustable by means of the adjusting screw 91 having its head on the back side of the machine.

To permit the hammer 14 and the channel knife 12 to be drawn back to allow the 120 insertion of the work, the following mechanism is provided: At 38 is shown a rock shaft provided with rearwardly extending lever 39 to which is attached the treadle connection 40 operated by a treadle 67 125 which may be termed the starting treadle. The rock shaft 38 is provided with two fingers 41 and 42. When the starting treadle is pressed down the finger 41 engages a small pin 43 on the side of the chan- 130

nel knife bar and slides the channel knife bar back on the pivot 28, which is in a slot 44 in the channel knife bar. The channel knife bar is held back as long as the treadle 5 is depressed. The other finger 42 on the rock shaft 38 contacts with the mushroom head 45 of a snap pin 46. The inner end of said snap pin 46 at times enters a shallow groove 47 in the side of the hammer 14. 10 When the starting treadle is depressed, the finger 42 moves out of engagement with the mushroom head 45 of the snap pin 46 so that the pin snaps into the groove in the hammer when the hammer is next drawn 15 back by the eccentric strap. Thereafter and as long as the starting treadle is depressed the hammer cannot move forward beyond a predetermined position because the end of the snap pin engages the rear 20 end of the groove 47. As soon as the starting treadle 67 is released, a spring 48 restores the finger 42 to its original position and pulls out the snap pin 46 so that thereafter the hammer may move forward and 25 engage the work.

The mechanism by which the position of the shoe relatively to that of the trimming knife is varied and by which the width of the edge *i. e.* the Scotch edge of Baltimore 30 edge is produced, will now be described.

At 15 is shown a stationary member which I term for convenience the feed stop and guide. This feed stop and guide is secured to the frame of the machine and is adjustable vertically by means of the screws 49 so that its position although normally stationary may be changed slightly as required. The feed stop and guide 15, see particularly Fig. 5 has a horizontal finger which 40 is conveniently oval in cross section and engages the underside of the trimmings which is cut off by the trimming knife. It also preferably engages the trimmed edge of the shoe and is located as close as possible to 45 the trimming knife 11. At 16 is shown the vertically movable crease guide, the face *f* of which rests against the upper on the last. I term this member for convenience the crease guide but it will be understood that 50 it may rest against the upper in which case it might be termed the last guide. From Figs. 2 and 5 it will be seen that the crease guide 16 is slotted and surrounds the anvil 13, being guided between the head of the 55 machine, which is shown at A and a front plate 51 secured to the head. The crease guide 16 is normally held in its highest position by means of a spring 52 contained in a hole in the plate 51 and engaging a lug 60 53 on the top of the crease guide. The upward movement of the crease guide is limited by a stop bolt 54 in a lug 55 on the head A of the machine, the usual lock nut 56 being provided. On the back of the crease 65 guide 16 is a stud 57 on which is a roll 58,

which is below and in engagement with a cam 59. This cam, as will be explained, is both bodily movable and rotatable, the movement of the crease guide from the shank trimming position to the Scotch edge 70 position being obtained by the bodily movement of the cam, while the Baltimore edge is produced by the rotation of the cam. This cam 59 is secured to the front end of a shaft 60, the rear end of which passes through a hole 62 in the frame of the machine, said hole being enlarged to permit the front end of the shaft 60 to be raised and lowered without binding. At 63 is shown a slide pin the lower end of which rests on the shaft 60. The forward end of a pressing lever 64 rests on the upper end of the pin 63 while the rear end of the pressing lever is pivoted at 65 to the frame of the machine. The pressing lever 64 is moved down when required by the operator by means of the control treadle 66 and link 67. The treadle 66 is the one previously described which controls the vertical position of the channel knife 12. A spring 68 is interposed between the link 67 and the pressing lever 64 so that after the pressing lever has reached the limit of its downward movement, the treadle may continue to move the rear end of the channel knife down. 95

On the shaft 60 is located a small rimmed pulley 69 around which is wrapped a chain or other flexible connection 70. The two ends 701 and 702 of the flexible connections pass over a two-grooved pulley 71 which is 100 mounted on a stud 72 on a boss on the front corner of the cover 73 which serves in part to guide the hammer 14. The two ends 701 and 702 of the flexible member 70 pass through a hole 704 in the front end of the 105 channel knife bar 25 and have secured to them two finger grips or medals 75 and 76 respectively. The finger grip 75 is marked L and the grip 76 is marked R to indicate which grip is to be used on the right shoe and which on the left. The hole 74 in the channel knife bar 25 is of oval cross section as is seen in Fig. 1, and is flared somewhat on the left hand side of the channel bar, as is seen in Fig. 2. It is also divided by a small partition 92, said partition being located near the right hand side face of the channel knife bar. The grips or medals are each tapered slightly as shown at *g* and are of such a size that they may enter the flaring hole 74 for 110 a short distance. Therefore whenever the operator draws one finger grip away from the hole 74 and the other finger grip is drawn back into the flaring hole 74, the grip will be in vertical position with its flat face 115 substantially parallel to the sole of the shoe and closely adjacent to it, so that the workman may conveniently seize the finger grip with its fore finger holding the finger grip against the bottom of the shoe. The parts 120 125 130 135 140 145 150 155 160 165 170 175 180

will always be in this position just before the beginning of the formation of the Baltimore edge. As the shoe advances through the machine during the formation of the 5 Baltimore edge the finger grip will be pulled out with the shoe and the cam shaft 60 will be rotated an amount determined by the length of the flexible connection. The length of the flexible connection may be adjusted by some suitable means as for instance 10 by the thumb screw 93 which moves the sleeve 94 on which the two-grooved pulley 71 is mounted. The rotation of the cam shaft in one direction pushes down the cam 15 roll 58 and therefore the crease guide 16 and increases the width of the edge left on the sole by the trimming knife. The rotation of the cam shaft 60 in the other direction allows the crease guide 16 to be raised by the 20 spring 52 and therefore the width of the edge is progressively diminished.

The grips 75 and 76 are preferably concave on both sides and are also knurled or roughened at h as will be seen in Fig. 2 so 25 that the operator may hold the grip immovably in place against the sole of the shoe.

As will be seen from the drawings, the cam roll 58 is located beneath the cam 59 and when the pressing lever 64 is at its lowest position the collar 80 so stops its further movement and supports the pressure of the operator's foot in case he stands on the 30 treadle, as frequently happens. This arrangement is a great advantage because there 35 can never be any undue pressure put on the cam shaft 60 or intermediate parts.

The collar 80 is adjustable vertically on the pin 63 which is screw threaded there being a set screw 95 to hold it in place when 40 once adjusted. The position of this collar determines the width of the Scotch edge. Also it starts the next shoe in the right position to begin the Baltimore edge having finished the Baltimore edge on the preceding shoe.

At 110 is shown heating means as a gas burner by means of which the crease guide 16 may be heated to iron the portion of the upper with which it contacts. Small 50 wrinkles frequently occur at the toe and elsewhere which may be thus ironed out easily especially if the shoe is not fed forward too fast or if it is drawn back and fed forward once or twice as may be easily done 55 since the feeding is done by hand.

The operation of my machine is as follows: Assuming that the right shoe is the first one to be trimmed, the machine begins at the heel end of the inside of the shank, 60 works along the shank, then along the inside of the ball, then around the toe along the outside of the ball, and finally along the shank to its heel end. The machine is then in position to begin the operation on the 65 left shoe. This takes place in the reverse

order. To insert the work the operator depresses the channel knife bar 25 by the action of the finger 41 which engages the pin 43. The depression of the treadle also allows the snap pin 46 to catch the hammer 70 14 on its next backward movement and prevents the hammer advancing while the work is being put in place. The work is then inserted with the upper at the heel end of the shank, against the crease guide 16, the 75 welt and sole being on the back side of the crease guide 16 and the anvil 13. The starting treadle is then released. The hammer 14 compresses the welt and sole against the anvil and clamps the work in stationary 80 position. While the shoe is stationary the channel knife moves horizontally and makes the first cut of the channel which is at a distance from the edge of the shank. At the same time the trimming knife cuts through the edge of the sole. The next rotation of the machine withdraws the trimming knife and the hammer so that the operator can feed the shoe forward. He then moves the shoe forward for a distance depending on his skill and the character of the work, but which is less than the width of the trimming knife, since the feed stop and guide prevents it being advanced farther. This 85 feed movement which in the machine shown in the drawings is produced wholly by hand, takes place while the channel knife is swinging back to its original position preparatory to making the next cut. After the shoe has been fed forward the hammer and trimming knife again advance and the channel knife makes the succeeding cut, this 90 cycle of movement being rapidly repeated. As soon as the first cut has been made the feed stop and guide passes into the space 95 between the trimmings and the edge of the sole and thereafter the feed stop and guide plays an important part in the guiding of the shoe as well as by preventing it being fed too fast. The feed stop and guide and the crease form two points of support for the work, the former being stationary and the latter being movable. While the feed of this shoe forward as herein described, is a step-by-step motion it is in actual operation apparently continuous, because the machine makes a very quick succession of movements, and the work is fed forward by hand at substantially a uniform rate. It may be stopped at any point without injury to the 100 work and may be advanced slowly or rapidly without producing an appreciable difference in the quality of the work. When the working instrumentalities have reached 105 the end of the shank which is also the beginning of the ball, the operator depresses the other treadle 66, and this raises the channel knife 11, swinging it on the pivot 110 28, and brings the channel closer to the edge 115 of the sole. The depression of the treadle 120 125 130

also pulls down the presser lever 64 and the pin 63 until the collar 80 strikes the top of the head. This swings down the end of the cam shaft 60 and lowers the crease guide 5 against the pressure of the spring 52 for an amount determined by the position of the collar 80. Thereafter, as long as the parts remain in the position described the trimming knife will sever the sole at a uniform distance from the upper and will form the so-called Scotch edge along the inside ball and toe of the shoe, to the point where the Baltimore edge is to begin. The transition from the shank edge to the Scotch edge 10 will be gradual because the treadle is depressed as the shoe is advancing. The operator then continues to advance the shoe, swinging it properly to trim the toe of the shoe and to form a Scotch edge around the toe. If no Baltimore edge is to be formed on the shoe the treadle is held down until the beginning of the shank is reached on the outside of the shoe when the treadle is released and the parts return to the shank 20 trimming position as seen in Fig. 5. If a Baltimore edge is to be formed on the shoe, the following operation occurs. As soon as the operator has turned the toe of the shoe, he seizes the medal marker R, which is the 25 medal then in horizontal position, with one end in the hole 74. The operator then holds the medal firmly against the toe of the shoe with his forefinger as is indicated in Fig. 5, and continues to feed the shoe forward until 30 the beginning of the shank is reached. The movement of the shoe from the toe to the beginning of the shank draws out the flexible connection 70, revolves the cam 59, and progressively depresses the crease guide for 35 an amount determined by the shape of the cam. This operation continues until the end of the flexible connection is reached because the other medal 75 has brought up against the socket in the channel knife bar. The 40 operator then releases the treadle and the shank trimming operation takes place in the usual manner, completing the operation on the right shoe.

It will be seen that when the right shoe is 45 trimmed the parts are left with the cam in the position which it occupies at the end of the formation of the Baltimore edge. This is the correct position to begin the formation of the Baltimore edge on the left shoe, 50 this shoe being trimmed in the reverse direction. It will therefore be seen that the machine is particularly adapted to trim rights and lefts alternately but that if circumstances require a succession of rights or 55 lefts they can be trimmed by pulling the proper medal out after each shoe is trimmed to restore the cam 59 to the proper starting position.

The amount of Baltimore edge given to 60 the shoe is determined by the shape of the

cam. The particular shape of the Baltimore edge is also determined by the slope of the cam. If a gradual Baltimore edge is required the cam will be given a substantially uniform slope, but it may be given an abrupt 70 slope at any point where it is desired to form a relatively large Baltimore edge. The mechanism described forms the Baltimore edge in proportion to the length of the flexible connection which is pulled out. Thus if 75 the cam gives a Baltimore edge of a quarter of an inch on a shoe in which the Baltimore edge extends for a distance of four inches along the edge of the sole, it will give a Baltimore edge of three-quarters of a quarter 80 inch on a shoe having a Baltimore edge extending along three inches of the sole. By this means the amount of the Baltimore edge is proportioned to the length of the sole.

In Fig. 9 there is shown a modification of 85 my invention. In this form the feed stop and guide 111 is vertically movable by means of the two treadles 112 and 113, and the chains 114 and 115. The extreme top and bottom positions are adjusted by screw stops 90 116 and 117, and the springs 118 and 119 tend to hold the feed stop in its central position. By this arrangement the Baltimore edge may be produced even if the crease 95 guide is held stationary, since the feed stop and guide will then be slightly higher or lower than the trimming knife and each cut will therefore be slightly above or below the preceding cut.

What I claim is:

1. In a machine of the character described, a reciprocating trimming knife which is withdrawn from the work between strokes, a feed stop and guide for the work which comprises a member engaging the trimmings 105 and the newly trimmed edge of the work adjacent the point where the trimmings are severed from the work.

2. In a machine of the character described, a reciprocating trimming knife which is withdrawn from the work between strokes and a feed stop and guide engaging the trimmings closely adjacent the knife and furnishing a point of engagement for the work just behind the knife.

3. In a machine of the character described, a trimming knife, a feed stop and guide engaging the cut edge of the trimmings and the newly trimmed edge of the shoe closely adjacent the cutting point and forming a 110 point of support for the shoe and a second guide engaging the shoe, one of said two guides being movable to swing the shoe about the other guide.

4. In a machine of the character described, 115 a reciprocating trimming knife which is withdrawn from the work between strokes, the feed stop and guide for the work which comprises a stationary member engaging the trimmings closely adjacent the point 120 125

100

115

120

125

130

- where the trimmings is severed from the work.
5. In a machine of the character described, a reciprocating trimming knife which is withdrawn from the work between strokes, a stationary feed stop and guide engaging the trimmings closely adjacent the knife and furnishing a point of engagement for the work just behind the knife.
10. 6. In a machine of the character described, a trimming knife, a crease guide, means under the control of the operator to change the position of the crease guide with relation to the trimming knife and a feed stop and guide also engaging the work and forming a pivot upon which the work is swung when the crease guide changes its position.
20. 7. In a machine of the character described, guiding means for the work, comprising a guide, a cam to move the guide, and means constructed and arranged to be held in fixed relation with the work and by which the cam and guide are thereafter moved when the work is moved.
25. 8. In a machine of the character described, guiding means for the work, comprising a guide, a cam to move the guide and means constructed and arranged to be held in fixed relation with the work, and a flexible connection secured thereto by which the cam is thereafter moved when the work is moved.
30. 9. In a machine of the character described, guiding means for the work, comprising a guide, means for moving the guide, means constructed and arranged to be held in fixed relation with the work, and a connection between said last mentioned means and said means for moving the guide by which the means for moving the guide and the guide are thereafter themselves moved when the work is moved.
35. 10. In a machine of the character described, the guiding means for the work comprising a guide, means for moving the guide, a connection by which the said means for moving the guide is moved in correspondence with the movement of the work, and means for adjusting the length of said connection.
40. 11. In a machine of the character described, the guiding means for the work comprising a guide, a rotating cam to move the guide, and a pair of flexible connections one of which rotates the cam in one direction and the other of which rotates the cam in the other direction.
45. 12. In a machine of the character described, the guiding means for the work comprising a guide, a rotating cam to move the guide, a pair of flexible connections, one of which rotates the cam in one direction and the other of which rotates the cam in the other direction, and means for adjusting the length of said flexible connections to vary the amount of rotation of the cam.
50. 13. In a machine of the character described, the guiding means comprising a guide, means for moving the guide, a finger grip to be held against the work, and a flexible connection between the said finger grip and the said means for moving the guide whereby the guide is moved in correspondence with the movement of the work.
55. 14. In a machine of the character described, the guiding means for the work comprising a guide, means for moving the guide, a finger grip to be held against the work, a flexible connection between said finger grip and the work, and means for positioning the finger grip in a position parallel to the work and in position to be seized by the operator.
60. 15. In a machine of the character described, the guiding means for the work comprising a guide, a cam to move the guide, a pair of flexible connections, said flexible connections being provided with finger grips and means engaged by the finger grips to position the same parallel to the bottom of the shoe to be operated upon and in position to be seized by the operator.
65. 16. In a machine of the character described, the guiding means for the work comprising a guide, a cam to move the guide, a flexible connection to move the cam, a flat finger grip on said flexible connection and a member having therein a hole corresponding in shape with the shape of the finger grip, said flexible connection passing through said hole.
70. 17. In a machine of the character described, the guiding means for the work comprising a guide, a rotating cam to move the guide, a pair of flexible connections, one of which rotates the guide in one direction and the other of which rotates the guide in the other direction, finger grips on said flexible connections, and a member having a hole therein shaped to correspond to the shape of the said finger grips, said hole having a partition therein, one of said flexible connections passing through the hole on one side of the partition and the other of said flexible connections passing through the hole on the other side of said partition.
75. 18. In an outsole trimming machine, a trimming knife, a shoe guide, which is normally in the shank trimming position, treadle operated means to move the guide to another position to produce an edge of uniform width and hand operated means for producing the Baltimore edge.
80. 19. In an outsole trimming machine, a trimming knife, a shoe guide which is normally in the shank trimming position, and a rotatable, bodily-movable cam, acting on said guide, and by its bodily movement moving said guide from the shank trimming position to the position to produce an edge of uniform width, and by its rotation moving

- the guide progressively to produce a Baltimore edge.
20. In an outsole trimming machine, a knife, a shoe guide, a bodily movable rotatable cam actuating the shoe guide, a pressing lever moving the cam bodily and means movable in unison with the movement of the shoe through the machine to rotate the cam.
- 10 21. In an outsole trimming machine, a trimming knife, a shoe guide, a bodily movable rotatable cam by the rotation of which the guide is moved to vary the width of the edge produced, means for moving the cam bodily to produce an edge of uniform width, a stop to limit the movement of said means, and means for rotating the cam.
22. In an outsole trimming machine, a trimming knife, a shoe guide, a bodily movable rotatable cam acting on said guide, means for moving the cam bodily to position the guide for the formation of an edge of uniform width, and means to rotate the cam to form an edge of varying width.
- 25 23. In an outsole trimming machine, a trimming knife, a shoe-guide by the position of which the width of the edge left on the shoe is determined and means for moving the shoe guide a distance dependent on the distance which the shoe is fed, whereby the width of the edge is proportioned to the length of the shoe, said means being adapted to be held in fixed relation with the shoe and thereafter to be moved when the work is moved.
- 30 24. In an outsole trimming machine, a shoe guide, a spring to hold the guide in position adjacent the trimming knife, a bodily movable rotatable cam to move the guide away from the trimming knife, said cam being located above its point of engagement with the shoe guide, a pressing member acting on the said cam to move it bodily, means for rotating the cam, and a stop to limit the motion of the pressing member and by which the pressing lever is supported when the cam is being rotated.
- 40 25. In a machine of the character described, the combination with an unyielding support for the work, of a trimming knife and a hammer coöperating with said unyielding support, common means for
- 55 moving the hammer and trimming knife and a yielding connection by which the trimming knife may move relatively to the work after the hammer has engaged the work.
26. In a machine of the character described, the combination with an unyielding support for the work, of a trimming knife and a hammer, an eccentric actuating both said trimming knife and hammer, and a yielding connection by which the trimming knife is enabled to move relatively to the hammer after the hammer has engaged the work on the unyielding support.
- 60 27. In a machine of the character described, a work support, a trimming knife, and a hammer, common means for moving said trimming knife and hammer, a yielding connection between said trimming knife and hammer to permit the movement of the trimming knife relatively to that of the hammer, and means under the control of the operator for holding the hammer stationary and out of engagement with the work.
- 70 28. In a machine of the character described, a work support, a trimming knife, and a hammer, common means for moving said trimming knife and hammer, a yielding connection between said trimming knife and hammer to permit the movement of the trimming knife relatively to that of the hammer, and a snap pin under the control of the operator for holding the hammer stationary and out of engagement with the work.
- 75 29. In a machine of the character described, the combination with a trimming knife, a channel knife, a pivot for the channel knife, there being a slot in the channel within which said pivot is received, means for oscillating the channel knife, and means under the control of the operator for sliding said channel knife on said pivot in said slot to withdraw the channel knife from engagement with the work.
- 80 In testimony whereof I affix my signature, in presence of two witnesses.
- FELIX E. VALOIS.
- Witnesses:
- JOHN H. PARKER,
ALICE H. MORRISON.
